UNITED STATES PATENT OFFICE.

HENRY A. MINER, OF MALDEN, MASSACHUSETTS, ASSIGNOR TO MINER'S FRUIT NECTAR COMPANY, OF BOSTON, MASSACHUSETTS, A CORPORATION OF MAINE.

DESIGN FOR A DISH OR CUP.

No. 38,403.

Specification for Design.

Patented Jan. 8, 1907.

Application filed December 4, 1906. Serial No. 346,352. Term of patent 3½ years.

To all whom it may concern:

Be it known that I, HENRY A. MINER, a citizen of the United States, residing at Malden, county of Middlesex, and State of Massachusetts, have invented a new, original, and ornamental Design for Dishes or Cups, of which the following is a specification, reference being had to the accompanying drawing, forming a part thereof.

The figure is a perspective view of a dish or cup, showing my new design.

What I claim is—

The ornamental design for a dish or cup as shown.

HENRY A. MINER.
